GESELLSCHAFT, OF ESSEN-ON-THE-RUHR, GERMANY.

TYPEWRITING MACHINE.

1,427,398.

Specification of Letters Patent. Patented Aug. 29, 1922.

Application filed October 14, 1921. Serial No. 507,754.

To all whom it may concern:

Be it known that I, KARL AUGUST LEHMANN, residing at Essen, Germany, a citizen of the German Republic, have invented a certain new and useful Improvement in Typewriting Machines, of which the following is a specification.

This invention relates to certain improvements in typewriting machines hereinafter fully described.

Certain typewriters exist in which the type keys, and therewith the type levers, can be locked both by an automatic margin adjuster and by a special hand-operated device, in their position of rest. But in these machines, a special latch rail is required to lock the type keys and the type levers. The object of the present invention is to provide a machine of the kind mentioned which will not require a special latch rail and which by this reason is simpler in construction than existing machines. This object is attained by causing the locking of the keys and levers both by the margin adjuster and by the said special element to result from locking the universal bar.

The invention is illustrated in the drawing, in which,

Fig. 1 is a cross section through the machine, with the parts omitted which are not pertinent to the invention.

Fig. 2 is a section on line 2—2 of Fig. 1, looking from the right.

Fig. 3 is the same cross section as Fig. 1, with the parts in different positions.

Fig. 4 is a section on line 4—4 of Fig. 1, looking from above and on a larger scale.

Fig. 5 is a detail section of Figs. 1 and 3, with a part in another position.

The type levers B, connected as usual with the type keys C, are pivotally mounted on a partition wall A¹, connecting the side walls A of the machine frame. In the rear face of said wall A¹ is formed an arc-shaped groove a² of rectangular cross section in which engages the universal bar D formed of a correspondingly curved sheet metal strip. Each type lever B is provided with a nose b¹, with which said lever engages against the universal bar D, in moving from its position of rest to its writing position, thus moving said bar parallel to itself. To the bar D is riveted, as appears in the drawing, a guide pin d¹, which is guided in a hole a³ passing through the partition wall

A¹. Also, two levers d² are mounted on the bar D, symmetrically with respect to the center plane of the machine, each of said levers being pivotally connected at its end to a lever e¹. The levers e¹ are fast on a shaft E, mounted on centers a⁴ carried by the wall A¹, so as to be easily rotatable.

Finally, to one end of the shaft E is secured a lever e², against which bears the free end of a bent lever G, pivoted on a bolt secured in the side wall A in the axial line of the shaft E. The lever G is acted upon by a tension spring g¹, which tends to hold said lever in the position shown in the drawing, in which position its free end stands at a certain distance from the end of the lever e². To the lever G is connected a pull-rod g² the other end of which is connected to one arm of a two-armed lever H H¹ pivoted on the adjacent side wall. Against one arm of this two-armed lever bears the spring-pressed bolt J of an automatic margin adjuster, while the other arm H¹ stands a short distance away from the end of a lever N. The automatic margin adjuster has a nose k¹ adjustably secured to the carriage frame K, which nose, when engaged by a swinging abutment M, presses the bolt J downwardly. The lever N is fast on a pin n¹, rotatable and longitudinally movable against the action of a spring n³ in the adjacent side wall A (Fig. 4). The pin n' is provided with a knurled head n² for turning it. The head n² carries a stop finger n⁴, by which said head can engage in a vertical or in an inclined groove a⁵.

In writing, the parts take the position of Fig. 1, in which, in particular, the spring-pressed bolt J takes its upper position and in which, further, the head n² engages by its stop finger n⁴ in the vertical latch groove a⁵. When now a type key C is depressed, the corresponding type lever B is moved into the writing position, as usual. In its movement from its position of rest to its writing position, the type lever B engages, when it comes into the intermediate position shown in dotted lines in Fig. 3, the universal bar D with its nose b¹, and moves said bar, and with it the two levers d², parallel to itself in the direction of the arrow x (Fig. 1). This movement of the levers d² causes a swinging movement of the levers e¹, pivoted thereto, and of the shaft E and lever e², in the direction of the arrow y (Fig. 1).

The shaft E is not hindered in this movement by the lever G, since the latter takes, in the position mentioned of the bolt J and of the head n^2 and under the influence of 5 the spring g^1 an angular position (see Fig. 1), in which its free end is at a sufficiently great distance away from the free end of the lever e^2 . The type lever B accordingly strikes on the paper roll and the universal 10 bar D, moves in the direction of the arrow x , causes the several elements of the machine to be moved as necessary for writing. After release of the depressed key C, all of the 15 said parts return to their position of rest. 20 As soon as the bolt J is pressed downwardly, in the neighborhood of the line margin, by the engagement of the nose k^1 with the abutment M, the two-armed lever H H^1 is turned into the angular position 25 shown in Fig. 3, in the direction of the arrow z . This causes, through the rod g^2 , the lever G to be rocked in the opposite direction to the arrow y . Thereby the lever G is moved into the angular position shown 30 in Fig. 3, in which its free end engages the free end of the lever e^2 and thereby locks the shaft E in the angular position corresponding to said lever position. But by this locking of the shaft E, the universal bar D, 35 which is connected to said shaft by the levers d^2 and e^1 , is locked in the position shown in Fig. 3 also. Now when a type key C is depressed and the corresponding type lever B is moved into the intermediate position 40 shown in Fig. 3, in which its nose b^1 strikes against the universal rail D, the latter, in consequence of the locking of the shaft E, cannot move and the type lever B and the type key C are also locked. As soon 45 as, by returning the paper carriage, the nose k^1 of the margin adjuster has again moved away from the abutment M, the bolt J returns, under the influence of its spring, into its upper position shown in Fig. 1, and the 50 double lever H H^1 , together with the rod g^2 and the lever G, returns, under the influence of the spring g^1 , also into its original position shown in Fig. 1, in which the lever G no longer prevents rotation of the shaft E and lever e^2 .

When, in any position of the paper carriage, the type keys C and type levers B are to be locked, the pin n^1 is pulled out, by the head n^2 , against the action of the spring n^3 , so that the stop finger n^4 is disengaged from the vertical groove a^5 , and then turned until said finger stands opposite the inclined groove a^5 . Then said head is released and the bolt n^1 engages by the finger n^4 ,

under the influence of the spring n^3 , in said 60 inclined latch groove. The bolt n^1 is now secured in the angular position shown in Fig. 5, in which its lever N has turned the double lever H H^1 , with the rod g^2 and lever G, into the locking position. The depression 65 of any type key C, to cause the corresponding type lever B to strike the paper roll, is now impossible. When this locking of the type keys and levers is to be released, the bolt n^1 is turned back into the position 70 shown in Figs. 1, 3 and 4, whereupon the double lever H H^1 , together with the rod g^2 and lever G, return into their unlocking position shown in Fig. 1.

Claims:

1. In combination with the type lever actuating devices of a typewriting machine, type levers actuated by said devices, a universal bar normally displaced by said type levers on actuation of the latter by said 80 devices, and an independent dual control means for locking said bar and type levers, one of said control means being an automatic margin adjuster and the second of said control means being a manually controlled 85 device for locking at will said bar and type levers whether said first control is actuated or not.

2. In combination with the type lever actuating devices of a typewriting machine, 90 type levers actuated by said devices, a common bar normally displaced by said type levers, a common bar locking means, a bell crank lever actuating said bar locking means and a plurality of means for independently 95 operating the crank members of the bell-crank lever, said plurality of means comprising a margin adjuster means and a manual control means for actuating said bar locking means at will whether said adjuster 100 means is operated or not.

3. In combination with the type lever actuating devices of a typewriting machine, type levers actuated by said devices, a common bar displaced by said type levers when 105 in normal operation, a common bar locking means, a bell-crank lever actuating said bar locking means when actuated one way, and a plurality of means for independently contacting and operating the crank members of 110 the bell-crank lever one way, said plurality of means comprising a margin adjuster means, and a manual control means for actuating said bar locking means at will.

The foregoing specification signed at 115 Essen, Germany, this 13th day of September, 1921.

KARL AUGUST LEHMANN.
